UNITED STATES PATENT OFFICE.

MACIEJ ZABOY, OF ALLENTOWN, PENNSYLVANIA, ASSIGNOR OF ONE-HALF TO
WOJCIECH DANIEL, OF ALLENTOWN, PENNSYLVANIA.

COMBINATION FOUNTAIN-BRUSH.

1,342,492.

Specification of Letters Patent.

Patented June 8, 1920.

Application filed March 19, 1919. Serial No. 283,472.

To all whom it may concern:

Be it known that I, MACIEJ ZABOY, a citizen of Poland, residing at Allentown, in the county of Lehigh and State of Pennsylvania, have invented certain new and useful Improvements in Combination Fountain-Brushes, of which the following is a specification.

The primary object of the invention is to provide a brush having a removable fluid supply and convertible for use as a mop or polisher whenever desired.

A further object of the invention is the provision of a fluid supplying attachment for brushes adapted for regulation during the operation of the brush, a mop member being also provided for employment with the brush.

A still further object of the invention is the provision of a device serviceable either as a fountain brush, a combined brush and mop, or an ordinary scrubbing brush, the structure being readily disassembled when desired and being simple in construction rendering its manufacture inexpensive.

Some of the objects of the invention having been set forth, the invention will be now more fully described reference being had to the accompanying drawings and in which like reference numerals designate corresponding parts throughout the several views.

In the drawings,

Figure 1 is an end elevation of the invention with parts broken away,

Fig. 2 is a top plan view thereof,

Fig. 3 is a front elevation of the same,

Fig. 4 is a view similar to Fig. 3, with the mop removed and parts shown in longitudinal vertical section,

Fig. 5 is a top plan view thereof with the fluid reservoir removed,

Fig. 6 is a top plan view of the brush,

Fig. 7 is a side elevation of the reservoir detached,

Fig. 8 is an enlarged transverse sectional view illustrating the valve mechanism for the reservoir,

Fig. 9 is a sectional view thereof taken upon line IX-IX of Fig. 8,

Fig. 10 is a perspective view of the mounting casing for the reservoir with its handle member broken away, and

Fig. 11 is a perspective view of the mop-engaging member.

My invention broadly consists of a scrubbing brush 10 having a casing 11 mounted thereon for supporting a reservoir 12, the brush being operated by a handle 13 secured to said casing and suitable valve means being provided for controlling the fluid contents of the reservoir 12 applied to the brush 10.

The brush 10 has the usual bristles 14 projecting from the lower side of the back member 15 of the brush while perforations 16 through the back 15 permit fluid from the reservoir 12 to freely flow through the brush upon the bristles when admitted under suitable control into the casing 11. The casing 11 has an open bottom as illustrated in Fig. 8 of the drawings for seating upon the brush back 15 surrounding the perforations 16 thereof while the handle 13 projects upwardly at an angle centrally of one side of the casing 11.

The reservoir 12 preferably of cylindrical form is removably seated upon arcuate transverse rods 17 struck-up from the top of the casing 11 while a central outlet pipe 18 in the bottom of the spout projects into the casing 11 through a central opening 19 in the top thereof and is normally closed by a spring-pressed valve 20 within the casing 11. V-shaped springs 21 depend from the opposite ends of the reservoir 12 for resilient engagement in T-shaped slots 22 adjacent the opposite ends of the top of the casing 11, whereby the reservoir is detachably mounted in its operative position upon the said casing.

The valve 20 is carried by an arm 23 hinged as at 24 within the casing 11 at the side thereof to which the handle 13 is secured, springs 25 normally engaging the arm 23 for maintaining the valve 20 elevated and in its closed position seated upon the open end of the pipe 18 when the reservoir 12 is assembled upon the casing 11. A wire 26 has its lower end attached to a loop 27 upon the arm 23 inwardly of the hinge 24 adapted to be pulled for opening the valve 20 by a rod 28 attached to the upper end of the wire 26 and extending to any suitable point upon the lower side of the handle 13. A filling spout 29 in the top of the reservoir 12 is normally closed by a cap 30.

A mop-holder is provided for the brush 10 consisting of a strip 31 mounted for

wardly of the casing 11 upon rods 32 transversely slidable through said casing and having loops 33 rearwardly thereof. Operating means for the rods 32 consists of 5 a substantially U-shaped frame 34 having opposite loops 35 hinged in the loops 33 with an intermediate connecting portion 36 of the frame 34 having a flexible mop 37 formed of suitable material such as fabric folded over the connecting portion 36 for 10 passing beneath the bristles 14 and between the strip 31 and the casing 11.

Opposite free ends 38 of the frame 34 are pivoted to ears 39 intermediate the ends 15 of a lever plate 40 of arcuate form adapted to flatly engage the handle 13 when the mop is ready for use. A sliding collar 41 upon the handle 13 is resiliently pressed upwardly by means of helical spring 42 upon the 20 handle while feet members 43 at the bottom of the plate 40 are pivoted as at 44 to the collar 41.

The complete operation of the invention will be fully understood by this detailed 25 description thereof, the reservoir 12 containing suitable fluid 45 being mounted upright on the casing 11 over the brush 10 with the spring-pressed valve 20 normally closing the outlet pipe 18 thereof. When brushing 30 or scrubbing, the handle 13 is grasped for directing the movements of the brush 10 and upon pulling the rod 28, any desired amount of the fluid 45 is delivered through the pipe 18 because on the opening of the 35 valve 20, such fluid freely passing into the casing 11 and through the perforations 16 to the bristles 14. By forcing the upper ends 46 of the springs 21 inwardly, the latter are released from the openings 22 40 and the reservoir 12 removed from the casing, permitting the employment of the mop brush 10 without the reservoir. The mop 37 is released by swinging the lever plate 40 forwardly upon its pivots 44 and at which

times, the spring 42 expands while movement of the plate 40 shifts the frame 34 forwardly as well as the rods 41 and the strip 31, separating the said strip from the forward side of the casing 11, permitting the adjustment of the forward end of 50 the mop 37 between said strip and casing. Upon rearwardly swinging the plate 40, the strip 31 holds the mop between the strip and the casing 11, the spring 42 normally holding the plate 40 in contact with the 55 handle 13 in a manner that will be readily apparent. Mop 37 may be employed or not as desired but is serviceable in polishing floors as well as in the usual mopping operation and is adapted to be stretched 60 when in position beneath the bristles 14 by the reservoir of the frame 34 and the action of the spring 42 with the forward end of the mop secured by the strip 31.

Having thus described my invention what 65 I claim as new and desire to secure by Letters Patent is:—

1. A device of the class described comprising a brush, a casing carried by the brush back and having a keeper opening 70 formed adjacent each end, a tank having spring fingers detachably received in said openings and controlling means for supplying the water in the tank to said brush.

2. A device of the class described comprising a brush, a casing carried by the brush back and having a keeper opening 75 formed adjacent each end, struck-up portions formed in said casing, a tank supported on said struck-up portions, spring 80 fingers carried by said tank for reception in the keeper openings, and means for controlling the supply of water from the tank to said brush.

In testimony whereof I affix my signature.

MACIEJ ZABOY.
